UNITED STATES PATENT OFFICE.

HENRY G. BAUM, OF YORK, PENNSYLVANIA, ASSIGNOR TO PULLMAN MOTOR CAR COMPANY, OF YORK, PENNSYLVANIA, A CORPORATION OF PENNSYLVANIA.

HINGE FOR AUTOMOBILE-HOODS.

1,079,536.

Specification of Letters Patent.

Patented Nov. 25, 1913.

Application filed September 20, 1911. Serial No. 650,315.

To all whom it may concern:

Be it known that I, HENRY G. BAUM, a citizen of the United States, residing at York, in the county of York and State of Pennsylvania, have invented certain new and useful Improvements in Hinges for Automobile-Hoods, of which the following is a specification, reference being had therein to the accompanying drawing.

10 This invention relates to a hinge for use in the construction of hoods for covering and protecting the engine in self-propelled vehicles, such as automobiles, and the invention relates more particularly to that class of 15 hoods known as "folding-hoods" where the top and side members are hinged together.

The objects of the invention are to provide a hinge of this class that by the novel construction shall be rendered both dust and 20 water proof.

Another object of the invention is to so hinge the side members to the top members that the side members may be swung outward at an approximate right angle to the 25 side of the car, to give access to the engine without raising either of the top members.

Still another object of the invention is to provide an automobile hood hinge of this 30 class that shall be cheap, durable and efficient, consisting of few parts.

With these and other objects in view, my invention consists in certain construction and combination of parts as will hereinafter be fully described and claimed in the 35 annexed specification, and illustrated in the accompanying drawings which form a part of this application, and in which like figures of reference refer to corresponding parts in all of the views; but it is fully understood 40 that while I have here described my invention as shown, that I do not confine myself to the exact design, as slight changes may be made in the construction and arrangement of the several parts without departing from the 45 spirit of the invention.

In the drawings:—Figure 1, is a detail perspective view of a portion of the top and side members of an automobile hood embodying my invention. Fig. 2, is a bottom plan view of the same. Fig. 3, is a side elevation of the same. Fig. 4, is a cross sectional view taken on the line X—X of Fig. 3. Fig. 5, is a cross sectional view taken on the line Y—Y of Fig. 3.

The outer edges of the roof or top member 55 1, are rolled inwardly to form a tube 6, which is provided with the cut out portions 7, which are adapted to receive the hinge knuckles 8, that are formed on the upper edge of the side members 9; said side members 9, being pivoted or hinged to the top or roof member 1, by a binding or pivot rod 10, which extends through the tube 6, and the hinge knuckles 8.

It will be noted that the cut out portions 65 7, of the tube 6, are of such form as to allow the side members 9, to be swung outwardly in an approximately horizontal position, and yet the top and outward side of said tube 6, is closed which renders the joint both water 70 and dust tight; as the tube 6, acts as an eaves for shedding the water; and furthermore as the hood is viewed from the side, the hinge joints are hidden from view.

The inner diameter of the tube 6, is the 75 same size as the outside diameter of the knuckles 8, and thus the tube 6, embraces and swings upon the knuckles 8.

The tube 6, near its ends is slightly bent out of round to touch the rod 10, as shown 80 in Fig. 1.

Having thus described my invention, what I claim as new and desire to secure by Letters Patent is:—

In a hinge for automobile hoods, comprising 85 two sheets of metal, the edge of one sheet being rolled to form a tube, a rod placed in said tube and spaced therefrom, cut-out portions on the inner and lower sides of said tube, said cut-out portions being spaced 90 slightly from the other sheet of the hinge, tongues formed on the other sheet of metal, said tongues being bent to produce knuckles, the knuckles being disposed within the openings in the tube, between the tube and the 95 rod, the free edges of the knuckles being spaced slightly from the first-mentioned sheet of said hinge, the cut-out portions and the tongues, being cut at corresponding angles, whereby a water proof and dust 100 proof hinge is formed.

In testimony whereof I affix my signature in presence of two witnesses.

HENRY G. BAUM.
